G. E. NAGEL

CONCRETE CRIBBING

Filed August 26, 1925

Fig. 1.

Fig. 2.

UNITED STATES PATENT OFFICE.

GEORGE E. NAGEL, OF GREENVILLE, OHIO.

CONCRETE CRIBBING.

Application filed August 26, 1925. Serial No. 52,606.

This invention relates to an improved reinforced concrete cribbing, designed primarily for use in constructing retaining walls, such as used in connection with fills and embankments of railways, but it is to be understood that a cribbing set up from cribbing units, in accordance with this invention, can be employed for any purposes for which it is found applicable, and the invention has for its object to provide, in a manner as hereinafter set forth, a cribbing formed of header and stretcher units of the same shape whereby the units are interchangeable and expeditiously installed, as well as incidentally simplifying the manufacturing thereof on account of the header units corresponding in contour to that of the stretcher units.

A further object of the invention is to provide, in a manner as hereinafter set forth, a cribbing formed of header units and stretcher units, the former corresponding in contour to the latter and with each of the units having on one side thereof, at each end, a right angularly disposed flange providing means to retain the sections of the cribbing endwise as well as laterally.

Further objects of the invention are to provide, in a manner as hereinafter set forth, a cribbing unit capable of being employed as a header or stretcher, and which is simple in its construction, strong, durable, reinforced, thoroughly efficient in its use, expeditiously and conveniently installed, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is an elevation of a cribbing set up from cribbing units in accordance with this invention.

Figure 2 is a side elevation of a header or a stretcher unit in accordance with this invention, and further illustrating in dotted lines the reinforcing means for the body portion of the unit.

Figure 3 is a section on line 3—3, Figure 2.

Referring to the drawings in detail, 1 denotes an excavation in which is arranged an inclined cribbing 2 set up from header and 60 stretcher units, in accordance with this invention.

In Figure 1 of the drawings, the header units are referred to generally by the reference character 3 and the stretcher units 65 generally by the reference character 4.

The header units correspond in contour to the shape of the stretcher units, and, therefore, the said header and stretcher units are interchangeable, and owing to the fact that 70 they are of the same contour the cribbing can be readily set up.

The header, as well as the stretcher unit, comprises a molded rectangular body portion 5 of concrete, of the desired length, and 75 which is rectangular in cross section, as shown in Figure 3. The side faces of the body portion 5 are indicated at 6, 7, 8 and 9. The face 6 is of less length than the faces 7, 8 and 9, as the body portion 5 at each end 80 terminal thereof is formed with a short flange which is disposed at right angles with respect to the side face 6. The flanges are indicated at 10, 11, and the inner end face 12 of the former terminates in one end of the face 6 adjacent the end face 13 of the body portion 5. The inner end face 14 of the flange 11 terminates in one end of the side face 6, at a point adjacent the other end face 15 of the body portion 5. The side 90 faces of the flanges 10 and 11 are flush respectively with the side faces 7 and 9 of the body portion, and the outer end faces of the flanges 10 and 11 are flush respectively with the end faces 13, 15 of the body portion 5. 95

The side faces 7, 8 and 9 of the body portion 5 are uninterrupted from end to end. The length of either of the flanges is substantially the same as the width of the body portion 9, but the width of each of said flanges is materially less than the width of the body portion 5. 100

Embedded within the body portion 5 is a series of equally spaced supporting frames, referred to generally by the reference character 17 and each formed of a top, bottom and a pair of side frame members integral with each other. Each of the frames is rectangular in contour and the material from which the body portion 5 is set up extends through and engages throughout the walls of the openings formed by said frames 110

whereby these latter are rigidly anchored within the body portion. The frames, when positioned in the body portion, are vertically disposed and have a pair of opposed outer edges equally spaced from the side faces 7 and 9 of the body portion 5, and the other pair of opposed outer edges equally spaced from the side faces 6 and 8 of the body portion. The outer edges of the frames which are spaced from the side faces 7 and 9 of the body portion are spaced a greater distance from said side faces than the distance the other pair of opposed outer edges of the frames is spaced from the side faces 6 and 8 of the body portion 5. The outer frames 17 of said series of frames are positioned inwardly with respect, but in close proximity to the flanges 10 and 11. As the material from which the body portion 5 is formed extends through the frame 17, as well as encloses the frame, these latter are anchored in position. Each of said frames 17 is provided with four pairs of openings 19, 20, 21 and 22. A pair of openings is arranged in each of the frame members of the frame at the longitudinal median of such frame member. The openings in the top or in the bottom frame member of the frame are arranged a greater distance apart than the distance between the openings in either of the side frame members. Each of the openings is formed with a continuous wall of circular contour. The pair of openings 19 is arranged in horizontal alignment. The pair of openings 20 is arranged in horizontal alignment. The pair of openings 19 is arranged in superposed alignment with respect to the pair of openings 20. The pair of openings 21 is arranged in superposed alignment. The pair of openings 22 is arranged in superposed alignment. The pairs of openings 19 and 20 are disposed at right angles with respect to the pairs of openings 21 and 22. The openings of each pair are spaced from each other. The pairs of openings in one frame align with the pairs of openings in an adjacent frame whereby sets of aligning openings are provided.

Extending from one end to the other end of the body portion 5 is a set of pairs of cylindrical reinforcing rods. The rods of one pair are indicated at 23, those of another pair at 24, those of another pair at 25, and the rods of the remaining pair at 26. The number of pairs of rods corresponds to the number of pairs of openings formed in the frames. The rods 23 extend through the openings 19, the rods 24 through the openings 20, the rods 25 through the openings 21, and the rods 26 through the openings 22. The pairs of rods not only reinforce the body portion 5 but further constitute additional means for anchoring the supporting frames within said body portion.

As the header and stretcher units are of

uniform construction they can be interchanged when setting up the cribbing, or in other words the construction of the unit permits it to be employed as a header or a stretcher and which simplifies installation on account of all the units being exactly alike, and further incidentally simplifies the manufacturing of the header and stretcher units as these latter are uniform. The setting up of the unit with the two flanges provides an L-shaped head at each end thereof and which can be used to retain the sections endwise as well as laterally.

What I claim is:—

1. A cribbing unit comprising a concrete body portion of appropriate length, a series of opposed, spaced, continuous frames corresponding in contour to the cross sectional shape of and completely embedded in said body portion, each of the frame members of each frame arranged in parallelism with a face of said body portion and aligning with the corresponding frame member of an adjacent frame, the material forming said body portion extending through and engaging throughout the wall of the opening formed by each frame to rigidly anchor the latter within the body portion, and each of the frame members of each frame provided intermediate its ends with a set of spaced openings, and a series of sets of reinforcing bars disposed lengthwise of said body portion, each set of bars common to aligning frame members and extending through the openings in these latter.

2. A cribbing unit comprising a concrete body portion of appropriate length, a series of opposed, spaced, continuous frames corresponding in contour to the cross sectional shape of and completely embedded in said body portion, each of the frame members of each frame arranged in parallelism with a face of said body portion and aligning with the corresponding frame member of an adjacent frame, the material forming said body portion extending through and engaging throughout the wall of the opening formed by each frame to rigidly anchor the latter within the body portion, each of the frame members of each frame provided intermediate its ends with a set of spaced openings, and a series of sets of reinforcing bars disposed lengthwise of said body portion, each set of bars common to aligning frame members and extending through the openings in these latter, and the end terminal portions of said bars extended from the outer frames of the series of frames to the ends of said body portion.

3. A cribbing unit comprising a concrete body portion of appropriate length, a series of opposed, spaced, continuous frames corresponding in contour to the cross sectional shape of and completely embedded in said body portion, each of the frame members

of each frame arranged in parallelism with a face of said body portion and aligning with the corresponding frame member of an adjacent frame, the material forming said body portion extending through and engaging throughout the wall of the opening formed by each frame to rigidly anchor the latter within the body portion, and each of the frame members of each frame provided intermediate its ends with a set of spaced openings, and a series of sets of reinforcing bars disposed lengthwise of said body portion, each set of bars common to aligning frame members and extending through the openings in these latter, and each of the openings in said frame members being of like contour and formed with a continuous wall.

4. A cribbing unit comprising a concrete body portion of appropriate length, a series of opposed, spaced, continuous frames corresponding in contour to the cross sectional shape of and completely embedded in said body portion, each of the frame members of each frame arranged in parallelism with a face of said body portion and aligning with the corresponding frame member of an adjacent frame, the material forming said body portion extending through and engaging throughout the wall of the opening formed by each frame to rigidly anchor the latter within the body portion, and each of the frame members of each frame provided intermediate the ends with a set of spaced openings, and a series of sets of reinforcing bars disposed lengthwise of said body portion, each set of bars common to align-

ing frame members and extending through the openings in these latter, the set of openings in one frame member aligning with sets of openings in the corresponding frame members of an adjacent frame.

5. A cribbing unit comprising a concrete body portion of appropriate length and of rectangular cross section, a series of opposed, spaced, continuous frames corresponding in contour to the cross sectional shape of and completely embedded in said body portion, the outer frames of said series spaced adjacent the ends of said body portion, each of said frames including a top, a bottom and a pair of side frame members, the material forming said body portion extending through and engaging throughout the wall of the opening formed by each frame to rigidly anchor the latter within the body portion, each of the frame members of each frame provided intermediate its ends with a set of spaced openings, and a series of sets of reinforcing bars disposed lengthwise of said body portion, each set of bars common to aligning frame members and extending through the openings in these latter, the openings of the sets in the top and bottom frame members of each frame being spaced a greater distance from each other than the openings of the sets of the side frame members of each frame, and the set of openings in one frame member aligning with the set of openings in the corresponding frame member of an adjacent frame.

In testimony whereof, I affix my signature hereto.

GEORGE E. NAGEL.
